UNITED STATES PATENT OFFICE.

OSCAR R. HUKLE, OF LEXINGTON, KENTUCKY.

CARBURETER AND MIXER.

No. 904,960.

Specification of Letters Patent.

Patented Nov. 24, 1908.

Application filed March 30, 1908. Serial No. 424,130.

To all whom it may concern:

Be it known that I, OSCAR R. HUKLE, citizen of the United States, residing at Lexington, county of Fayette, and State of Kentucky, have invented certain new and useful improvements in Carbureters and Mixers, of which the following is a specification, reference being had therein to the accompanying drawing.

10 This invention relates to a carbureter and mixer, and particularly to a structure adapted for application to an internal combustion engine.

15 The invention has for an object to provide a novel and improved construction of means for feeding a hydrocarbon to carburet air and regulating such feed.

20 A further object of the invention is to provide a novel and improved construction of inlet valve and means for controlling the same from a governor together with a controlling disk mounted to coöperate with said valve.

25 Another object of the invention is to provide a coöperating mixer disposed relative to the discharge from the valve and in connection with means for automatically determining the proper proportions of air and hydrocarbon supplied to the engine.

30 Other and further objects and advantages of the invention will be hereinafter fully set forth and the novel features defined by the appended claims.

35 In the drawing:—Figure 1 is a vertical section with parts in elevation; Fig. 2 is an enlarged detail section of a portion of the valve and its seat taken at a right angle to Fig. 1; Fig. 3 is a vertical section of the valve seat; Fig. 4 is a horizontal section 40 through the valve; Fig. 5 is a bottom plan of the regulator disk mounted beneath the valve seat; Fig. 6 is a similar view of the valve seat; Fig. 7 is a section through this seat on line 7—7 Fig. 3; Fig. 8 is an elevation of the discharge from the fuel feed tube, and Fig. 9 is a top plan of this part.

45 Like numerals refer to like parts in the several views of the drawing.

50 The numeral 10 designates the valve casing which may be of any desired size or configuration and is provided at its upper portion with a mixing chamber 11 and at its lower portion with a fuel chamber 12, while intermediate of the mixer and fuel chamber 55 an air chamber 13 is provided and formed with an inlet 14 for air.

The lower end of the fuel chamber 12 is closed by a plate 15 secured to the casing 10, and depending from this portion is a well or casing 16 provided at its lower portion with 60 a liquid chamber 17 communicating with a supply pipe 18. Within the well 16 and extending into the fuel chamber 12 is a feed tube 19 having at its lower end a casing 20 provided with a check valve 21 and a cup or 65 piston 22 which in the downward movement of the tube collects the liquid and forces it past the valve until sufficient quantity accumulates to overflow at the upper open end of the feed tube. This tube is supported 70 and guided by a spider 23 mounted on the plate 15, while a spring 24 extends from the upper portion of this spider to the distributor plate 25 over which the fuel flows. This plate is provided with a cap 26 spaced 75 above the open end of the tube 19, as shown in Fig. 8 to prevent any upward spurt of the fuel toward the inlet of the valve. The feed tube 19 may be reciprocated by any desired means, but a preferable form thereof is 80 herein shown where the tube is provided with a stop or projection 27 adapted to bear against an arm 28 of the crank lever 29 which lever is mounted in a pivoting lug 30 carried on the plate 15. The upright arm 85 of the crank lever is provided with a friction roller 31 bearing in contact with a cam face 32 disposed upon a disk 33 formed at the end of the sleeve or collar 34 which extends within the bearing casing 35 mounted at one 90 side of the air chamber by means of the plate 36. The outer end of this sleeve 34 is attached to the extended hub 37 of the pulley 38 which is rotatably mounted upon the bearing portion 35. The operating cam for 95 the feed tube is thus actuated at a speed relative to the speed of the pulley and the feed consequently governed.

The hub 37 is provided with arms 39 adapted to support the governing weights 100 40 having the crank arms 41 mounted in the collar at 42 which is rotatable upon the valve rod 43 and held against longitudinal movement by set nuts 44 at the opposite sides of the collar. This valve rod is connected to a 105 valve operating lever at 45 and extends into a tubular adjusting nut 46 having therein a spring 47 by which the tension necessary to reciprocate the valve operating rod may be governed or determined.

110 Within the air chamber 13 the valve casing 48 is mounted. This casing, as shown in

Figs. 1 and 3 is provided with air ports 49 in its side walls and fuel ports 50 in its lower wall. This lower wall is also provided with an opening 51 through which the valve stem 52 extends. The valve seat 48 has a depending flange 53 provided with a slot 54 through which the operating handle 55 for the regulating disk 56 extends. This disk, as shown in Fig. 5, is provided with a series of fuel ports 57 and with a depending flange 58 adapted to receive the operating handle 55 which handle is provided with an indicator 59 mounted relative to an indicator plate 60 upon the casing 10, as shown in Fig. 2. This disk is provided with a central opening 61 through which the valve stem 62 passes, and the disk is supported in yielding contact with the under face of the valve casing by means of a tension spring 62 disposed between the 20 disk and crank arm 63 which embraces and is pivotally connected with the valve shifting rod at 45. The valve 64 is cylindrical and provided with air ports 65 in its side walls and fuel ports 66 in its bottom adapted to coöperate with the ports in the seat and disk. 25 The valve is also provided with a centrally extended hub 67 keyed to the stem 52 to rotate therewith and held against vertical displacement thereon by means of the nut 68 threaded upon the end of said stem.

The mixing chamber 11 is provided with the perforated plates 70 spaced from each other and disposed diagonally above the outlet from the valve so that they effect a thorough mixture of the air and fuel before it is carried from the connection 71 to the engine. These plates are supported by a lug 72 depending from the cap plate 73 mounted upon the casing to close the upper portion thereof 40 and spaced apart by a block 74. The removal of this cap plate permits access to the valve and other parts within the apparatus.

In the operation of the invention it will be seen that the governor pulley automatically feeds the fuel from the well and discharges it over the distributor plate at the upper end of the feed tube from whence it is brought by suction into the valve and coming in contact with the air from the chamber 50 surrounding the valve thoroughly carburets the air and forms a mixture which is completed in the passage through the perforated plates. The surplus of the fuel which is not vaporized and drawn into the valve flows 55 back to the well by gravity, while the valve is controlled from the governor connection relative to the load upon the engine so that the desired proportion of air and fuel may be at all times maintained. When it is necessary to vary this proportion it can be effected by a proper shifting of the governing disk beneath the valve by which the relative amount of fuel entering the valve may be controlled and indicated upon the outside of 60 the casing. By means of this disk the

charge to be mixed can be controlled or entirely shut off. The operation of the vertically disposed valves brings the ports into proper alignment and being oscillatory the bearings are equally distributed throughout 70 their entire surfaces insuring absolute even wear at all points. The weight of the valve resting upon its end compensates by its gravity for all wear that is effected in use and consequently fits its seat leaving no space in 75 which overflow can find lodgment to cause sticking. The fuel ports are so disposed that their alignment is completely controlled by the governor and the opening and closing can be regulated by the manipulation of the 80 indicator as the load carried may require.

Having described my invention and set forth its merits, what I claim and desire to secure by Letters Patent is:—

1. In a device of the class described, a casting, a fuel well carried thereby, a valved feed tube mounted to reciprocate in said well, a lever adapted to operate said tube, a driving pulley, a sleeve secured to said pulley, and means upon said sleeve to actuate 85 said lever.
2. In a device of the class described, a casting, a fuel well carried thereby, a valved feed tube mounted to reciprocate in said well, a lever adapted to operate said tube, a 95 driving pulley, a sleeve secured to said pulley, and a cam carried by a disk at the inner end of said sleeve to engage a crank arm from said lever.
3. In a device of the class described, a casting, a fuel well carried thereby, a valved feed tube mounted to reciprocate in said well, a lever adapted to operate said tube, a driving pulley, a sleeve secured to said pulley and having means to actuate said lever, 100 a spring to normally support said tube in raised position, and a lug carried by said tube to engage said lever.
4. In a device of the class described, a casting, a fuel well carried thereby, a valved feed tube mounted to reciprocate in said well, a lever adapted to operate said tube, a 110 driving pulley, a sleeve secured to said pulley, means upon said sleeve to actuate said lever, and a conical distributing plate secured at the upper end of said tube. 115
5. In a device of the class described, a casting, a fuel well carried thereby, a valved feed tube mounted to reciprocate in said well, a lever adapted to operate said tube, a 120 driving pulley, a sleeve secured to said pulley, means upon said sleeve to actuate said lever, a conical distributing plate secured at the upper end of said tube, and a cap disposed above the upper end of said tube and 125 spaced from said plate.
6. In a device of the class described, a casting, a fuel well carried thereby, a valved feed tube mounted to reciprocate in said well, a lever adapted to operate said tube, a 130

driving pulley, a sleeve secured to said pulley, means upon said sleeve to actuate said lever, a vertically disposed valve above said tube, a reciprocating rod for operating said valve, and a governor weight carried by said pulley for actuating said rod.

7. In a device of the class described, a casing, a fuel well carried thereby, a valved feed tube mounted to reciprocate in said well, a lever adapted to operate said tube, a driving pulley, a sleeve secured to said pulley, means upon said sleeve to actuate said lever, a vertically disposed valve above said tube, a reciprocating rod for operating said valve, a governor weight carried by said pulley for actuating said rod, and diagonally disposed mixer plates above said valve.

8. In a device of the class described, a casing, a fuel well carried thereby, a valved feed tube mounted to reciprocate in said well, a lever adapted to operate said tube, a driving pulley, a sleeve secured to said pulley, means upon said sleeve to actuate said lever, a vertically disposed valve above said tube, a reciprocating rod for operating said valve, a governor weight carried by said pulley for actuating said rod, and a regulating plate disposed beneath said valve to control the fuel feed thereto.

9. In a device of the class described, a casing provided with a depending fuel well, a feed tube provided at its lower end with a check valve and a cup within said well, means for supporting the upper end of said tube, a distributing plate at said upper end, a lifting spring between said plate and supporting means, and means for reciprocating said tube.

10. In a device of the class described, a casing provided with a depending fuel well, a reciprocating valved feed tube mounted in said well and provided with a projection, a crank lever mounted with one arm to engage said projection, a bearing carried by said casing, a sleeve in said bearing provided with a cam disposed within the casing to engage said crank lever, and a driving pulley rotatably mounted upon the outer surface of said bearing and connected to the extended end of said sleeve.

11. In a device of the class described, an air chamber, a fuel chamber, an oscillating valve disposed in the air chamber and having air ports in its side and fuel ports at one end communicating with the air and fuel chambers respectively, a mixing chamber communicating with the delivery from said valve, a stem from said valve provided with a crank arm, a reciprocating rod pivoted to said arm, a governor device mounted for reciprocating said rod, and a tubular adjusting screw provided with a tension spring and adapted to receive an end of the operating rod.

12. In a device of the class described, an

air chamber, a fuel chamber, an oscillating valve disposed in the air chamber and having air and fuel ports communicating with the air and fuel chambers respectively, a stem from said valve provided with a crank arm, a reciprocating rod pivoted to said arm, a governor device mounted for reciprocating said rod, a regulating plate disposed beneath the fuel ports, and an operating handle extending from said plate and provided with an indicator thereon.

13. In a device of the class described, an air chamber, a fuel chamber, an oscillating valve disposed in the air chamber and having air and fuel ports communicating with the air and fuel chambers respectively, a stem from said valve provided with a crank arm, a reciprocating rod pivoted to said arm, a governor device mounted for reciprocating said rod, a regulating plate disposed beneath the fuel ports, an operating handle extending from said plate, and a tension spring disposed between the crank arm of the valve stem and said plate.

14. In a device of the class described, an air chamber, a fuel chamber, an oscillating valve disposed in the air chamber and having air and fuel ports communicating with the air and fuel chambers respectively, a stem from said valve provided with a crank arm, a reciprocating rod pivoted to said arm, a governor device mounted for reciprocating said rod, a regulating plate disposed beneath the fuel ports, an operating handle extending from said plate, an indicating head carried by the operating arm for said regulating plate, and a coöperating indicating plate upon the casing.

15. In a device of the class described, a casing provided with a fuel chamber, a fuel well depending from said chamber, a pump for raising fuel from said well to said chamber, an air chamber provided with an inlet valve having air and fuel ports communicating with said fuel and air chambers, respectively, a mixing chamber above said valve, and driven means for positively actuating said pump.

16. In a device of the class described, a casing provided with a fuel chamber, a fuel well depending from said chamber, a pump for raising fuel from said well to said chamber, an air chamber provided with an inlet valve communicating with said fuel chamber, a mixing chamber above said valve, means for controlling said valve, and parallel perforated plates supported in the mixing chamber above said valve and diagonal to the vertical axis thereof.

17. In a device of the class described, a casing provided with a fuel chamber, a fuel well depending from said chamber, an air chamber provided with an inlet valve communicating with the fuel chamber and controlling the air and fuel supply, a mixing

chamber above said valve and communicating therewith, means for feeding from said well and controlling said valve, a cap plate provided with a depending lug, and spaced 5 perforated mixing plates carried by the lower end of said lug diagonal to the vertical axis of said valve.

18. In a device of the class described, a casing provided with an air chamber, a fuel 10 chamber, a cylindrical valve seat in said air chamber having side and bottom walls each provided with ports communicating respectively with the air and fuel chambers, a valve disposed in said seat and provided 15 with side and bottom walls each having ports therein communicating with the seat ports, a valve stem extending through said seat and connected to oscillate said valve, governor controlled means for actuating said stem, 20 and means for adjusting the fuel ports in said seat.

19. In a device of the class described, a casing provided with an air chamber, a fuel chamber, a cylindrical valve seat in said air 25 chamber having side and bottom walls each provided with ports communicating respectively with the air and fuel chambers, a valve disposed in said seat and provided with side and bottom walls each having 30 ports therein communicating with the seat ports, a valve stem extending through said seat and connected to oscillate said valve,

governor controlled means for actuating said stem, a regulating disk disposed beneath said valve seat and provided with fuel ports, 35 a depending lug from said disk, and an operating rod extending outward from said lug.

20. In a device of the class described, a casing provided with an air chamber, a fuel 40 chamber, a cylindrical valve seat in said air chamber having side and bottom walls each provided with ports communicating respectively with the air and fuel chambers, a valve disposed in said seat and provided 45 with side and bottom walls each having ports therein communicating with the seat ports, a valve stem extending through said seat and connected to oscillate said valve, governor controlled means for actuating said 50 stem, a regulating disk disposed beneath said valve seat and provided with fuel ports, a depending lug from said disk, an operating rod extending outward from said lug, a depending flange from said seat to receive 55 said disk, and a tension spring upon said stem to support said disk in yielding contact with the valve seat.

In testimony whereof I affix my signature in presence of two witnesses.

OSCAR R. HUKLE.
